UNITED STATES PATENT OFFICE.

JOSEPH DONALD SMITH, OF ST. MARYS, ONTARIO, CANADA, ASSIGNOR OF ONE-HALF TO
JOHN K. RICHARDSON, OF ST. MARYS, ONTARIO, CANADA.

SHEET-METAL PIPE.

Application filed July 27, 1927. Serial No. 208,856.

The principal object of the invention is to provide a simple and effective lock for the seam of a collapsible sheet metal pipe which will effectively secure the joint against separation and which will not add materially to the cost of producing the pipe.

The principal features of the invention consists in providing a rectangular sheet of metal with two parallel edges turned back to form flanges, one of said edges being provided with narrow lug extensions which project beyond one of said flanges and are adapted to be bent back over the edge of the other flange to lock the two flanges against separation.

In the drawings, Figure 1 is a perspective view of a sheet metal pipe constructed in accordance with this invention.

Figure 2 is an enlarged sectional detail of the seam and locking means showing the same before being locked.

Figure 3 is a view similar to Figure 2 showing the manner in which the seam is locked.

Figure 4 is a fragmentary elevational view of the interior of the pipe showing the edges prior to being connected together and showing the disposition of one of the locking lugs.

Figure 5 is a fragmentary view on a reduced scale of one of the meeting edges of the pipe showing the arrangement of the locking lugs at either end.

In the manufacturing of sheet metal pipes it has been found desirable to provide the pipes with separable joints or seams.

Such pipes may be packed into compact form for shipping purposes and in setting up the pipes it is necessary to provide some form of lock to prevent the separation of the seam and various provisions have been made for locking the seams together.

The present invention is directed to a simple locking means for a pipe of this type and in carrying the invention into effect the sheet of metal from which the pipe is made is formed with lug extensions 1 which are bent back from the edge 2 of the sheet in flat overlapping relation.

These lug extensions are preferably arranged one at each end of the sheet in order to render the same readily accessible for reasons to be described later.

The sheet is rolled into a substantially cylindrical form with the lugs 1 disposed on the inside thereof and is provided with the usual beads 3 which partially encircle the

pipe and terminate a short distance from the edges of the pipe.

The opposing edges of the pipe are then bent back in the usual manner as shown in Figure 2 to provide the mating flanges 4 and 5.

It will be noted that the base portion of the lug extension 1 is incorporated in the flange 5 and the remaining free end 6 thereof projects freely therebeyond as shown in Figures 65 and 4 of the drawings.

When it is desired to complete the pipe the flanges 4 and 5 are intermeshed to provide a close joint throughout the length of the pipe and the joint is then securely locked against separation by simply bending the free extending portion 6 of the lug 1 back over the opposed portion of the flange 4 as shown in Figure 3 of the drawings.

A very secure lock is thus obtained and it will be impossible for the joint, when thus secured, to become accidentally separated and the locking means, being positioned adjacent the ends of the pipe, will be readily accessible for locking purposes.

The present invention is particularly applicable for use with stove pipes but may be employed equally successfully on numerous forms or sizes of sheet metal pipes without departing from the spirit of the invention as set forth.

What I claim as my invention is:

1. In a sheet metal pipe, a sheet of metal bent into cylindrical form and provided with seam forming edges, and having portions of the body of said sheet continuing beyond one of said edges and forming free integral lug extensions bent back over the other edge to secure the joint against separation.

2. In a sheet metal pipe, a sheet of metal bent into cylindrical form and having portions of the body thereof continuing beyond one edge and forming lug extensions integral therewith, the latter being turned backwardly from one edge thereof to overlap the adjacent body portion, the meeting edges of the pipe being flanged longitudinally to form a seam, said lug extensions extending freely beyond the flange formation and bent over one of the flanged meeting edges to lock the joint against separation.

3. In a sheet metal pipe, a sheet of metal bent into cylindrical form and having the meeting edges thereof flanged backwardly to engage each other in a longitudinal joint,

said sheet having portions of the body continuing beyond one of said edges and bent backwardly therefrom and incorporated in the flange and forming lugs extending beyond the flange edge bent over the opposite flanged edge to engage the same to prevent the separation of the joint.

4. A lock for the seam of sheet metal pipes, comprising the combination with the 10 seamed meeting edges, of lug extensions formed by integral continuations of the body portion of said sheet beyond one of said meeting edges the latter being turned inwardly and extending beyond the seamed edge and 15 bent over the other seamed edge to secure the joint.

5. In a sheet metal pipe, a sheet of metal bent into cylindrical form and having one edge flanged outwardly and backwardly, said sheet having portions of the body extending beyond the other edge in the form of lugs, the latter being bent backwardly in close overlapping contact with the inner wall of the pipe, said latter edge being flanged inwardly and backwardly the opposing portion of said lugs conforming to the inner wall of said flange the remaining portion of said lugs being free and bent forwardly and embracing the first mentioned flange to prevent its disengagement from the latter flange. 20 25

JOS. DONALD SMITH.
